UNITED STATES PATENT OFFICE

KARL F. JUENGLING, OF LAKWOOD, OHIO, ASSIGNOR TO ARTHUR G. MCKEE AND COMPANY, OF CLEVELAND, OHIO, A CORPORATION OF DELAWARE

DISTRIBUTOR MOUNTING FOR BLAST-FURNACE STACKS

Application filed May 10, 1928. Serial No. 276,633.

This invention relates broadly to charge feeding and distributing mechanism for blast furnaces. More particularly, it has to do with the provision of an anti-friction supporting structure or mounting for the hopper which operates in conjunction with the usual bell gate for controlling the introduction of raw materials, and suitably distributing such materials over the contents of a second and lower hopper from which the charge is fed into the stack.

The dust laden atmosphere in which this distributing mechanism operates, together with the necessity for continuous or uninterrupted operation of the furnace, make necessary the provision of a distributor mounting that will effectively resist the deleterious action of dust and other destructive agencies, on the one hand, and yet, on the other hand, provide for the ready replacement or repair of such parts as are subject to wear or most likely to become unserviceable. To these ends I have provided an improved anti-friction support or mounting for the revolute hopper of a distributor which consists essentially of a number of separately removable roller units that have been specially designed for excluding dust and facilitating the making of any necessary repairs or replacements. I have also provided, for coaction with said rollers, a track or race of such design that its replacement or repair is also facilitated, and thus the entire structure rendered more dependable and convenient to service without material interference with the continuance of blast furnace smelting operation.

In the accompanying drawings wherein one embodiment of my invention is illustrated and wherein similar reference numerals designate corresponding parts in several views:

Fig. 1 is a fragmentary elevational view showing my improved mounting for the revolute hopper of the distributor and also one form of apparatus for driving and controlling the movements of such hopper; Fig. 2 is a fragmentary plan view showing one of the removable roller units in its relation to other parts of the mechanism; and Fig. 3 is a

vertical sectional view taken on line 3—3 of Fig. 2, and showing in detail the construction of one of the several identical roller units and the track or race with which it co-operates.

In the drawings, and with particular reference to Figs. 1 and 3, my invention is shown in association with a gas seal or cover 1, which may form the upper part of the usual two vertically disposed hoppers on top of the blast furnace stack. Mounted upon the cover 1 is a flanged neck piece 2 that carries an annulus or base member 3 having oppositely extending parts 4 and 5. The part 4 constitutes a flange from which project a plurality of radially arranged brackets 6 that are designed for supporting the roller units or hopper bearings hereafter described. The part 5 of base member 4 extends inwardly and forms one of two complementary gas obstructing flanges 6 and 7 for assisting in preventing the escape of gas from the lowermost hopper and from the furnace. The flange 7 projects laterally from the cylindrical bell seat member 8 which may have a telescoping relation with the neck piece 2, and whose top may be provided with a second flange 9 for a purpose to be hereafter explained. The bell seat member 8, together with its extension 10, constitutes a distributor for feeding raw materials past the bell gate (not shown) and into the lower hopper from which such materials may pass directly into the stack of the furnace. Loosely encircling the bell seat member 8 may be a segmental sealing ring 11 that rests upon the flange 6 and supplements the action of the two complementary flanges 6 and 7 in preventing the escape of gas.

Removably secured to the flange 9 of the bell seat member 8 is an annular gear 12. This gear, and therefore the distributor to which it is attached, may be given suitable movements, either rotary or oscillatory, by an intermeshing smaller gear or pinion (not shown) that receives its motion from an electric motor 13 through a universal coupling 14 and encased worm and worm wheel reduction gearing, this drive, the brake 15 and motor controlling limit switch 16 being preferably assembled as a unit with the base mem-

ber 3, all substantially as described in prior United States Patents Nos. 1,563,424 and 1,622,461 to A. G. McKee, respectively dated Dec. 1, 1925 and March 29, 1927. The gear 5 12 may be provided with a circumferential channel or groove 17 for receiving part of the thickness of a track or race 18 whose lower face 19 operates against or in contact with revoluble rollers 20, of which there may be 10 any desired number, say six, spaced around the outside flange of the base member 3. It will be understood that the track 18 may be of detachable design, it being secured to the gear 12 in any approved manner, as for example by stud bolts 21. For maintaining the bell seat member 8 in properly centered relation to the neck piece 2 and base member 3, the track 18 may have its inner edge provided 15 with a shoulder for contacting with the similarly shaped inner edge of the rollers 20, this shoulder also assisting in obtaining a proper adjustment of the rollers 20.

The rollers 20 may be secured upon shafts 22 in any suitable manner and prevented from 20 moving lengthwise thereof by split rings 23 or the like. The roller shafts 22 may be journaled in roller or other suitable bearings 24 positioned in sleeves 25 in boxes or housings 26, such boxes being preferably provided with 25 caps 27 and 28 for their outer end closures and inwardly directed flanges 29 and 30 for fitting closely to the shafts 22 in order to exclude dust and confine the lubricant injected through tubes 31 or otherwise supplied to the 30 bearings. For taking the shaft end thrust incident to the inclination of the line of contact between the rollers 20 and their track 18, as well as for making possible some longitudinal adjustment of the shafts 22, there may 35 be provided some such arrangement as thrust blocks 32 regulated by screws 33 and secured in any adjusted position by nuts 34. As shown in Fig. 2, each pair of boxes 26 may be formed in one piece with a bearing block 40 35 having lugs 36 that may be bolted or otherwise secured to the base member 3. These blocks are preferably separate from each other and removably secured to the brackets 6 of the base member 3 so that in event of 45 the failure of any one or more of the rollers, their shafts or bearings, the objectionable or defective unit can be removed and immediately replaced by a spare or extra block of 50 the same kind. This can be accomplished, as can be seen in the drawings, particularly in Figs. 1 and 3, by merely unfastening the block and removing it laterally, it being unnecessary to elevate, move or otherwise disturb the relative positions of the bell seat 55 member 8 or the base member 3.

It will thus be seen that my invention provides for easily making any necessary corrections in the distributor mounting while at the same time obtaining the advantage of simple design and dependable operation due to 60

the exclusion of dust and other abrasive materials which might damage the moving parts.

Other modes of applying the principle of my invention may be employed instead of the one explained, change being made as regards 70 the mechanism herein disclosed, provided the means stated by any of the following claims or the equivalent of such stated means be employed.

I therefore particularly point out and distinctly claim as my invention:—

1. In blast furnace charging mechanism, the combination of a revoluble distributor having a radially inclined annular track provided with an annular flange, a conical roller beneath said track in engagement therewith and said flange for radially and axially supporting said distributor, a journal pin carrying said roller, a housing adapted to receive the end of said journal pin, brackets united 80 integrally with the base member for supporting said housing, said housing adapted to be removed from said bracket.

2. In blast furnace charging mechanism, the combination of a revoluble distributor 90 having a radially inclined annular track, an axially extending flange united integrally with the inner edge of said track, a conical roller beneath said track for supporting said distributor and adapted to engage said flange, 95 a journal pin for carrying said roller, a removable housing adapted to receive the end of said journal pin, a bracket united integrally with the base member for supporting said housing, and said housing adapted to 100 be removably connected to said bracket.

3. In blast furnace charging mechanism, the combination of a revoluble distributor having a radially inclined annular track, an axially extending flange united to the inner 105 edge of said track, a conical roller beneath said track for supporting said distributor, a shoulder formed on the reduced end of said roller for contacting with the axially extending flange of said track, a journal pin for carrying said roller, a removable housing adapted to receive and rotatably support the end of said journal pin, a bracket united with the base member for supporting said housing, and said housing adapted to be remov- 110 ably connected to said bracket.

Signed by me this 8th day of May, 1928.
KARL F. JUENGLING.
